US0D1049130S

(12) **United States Design Patent** (10) Patent No.: US D1,049,130 S
Altonen et al. (45) Date of Patent: ** Oct. 29, 2024

- (54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Gregory Altonen**, Easton, PA (US); **Brad Michael Kreschollek**, Bethlehem, PA (US); **Karelys Alfonzo**, Coopersburg, PA (US); **Nayda Aponte**, Northampton, PA (US); **Xiangzhu Chen**, Allentown, PA (US); **Bryan Robert Barnes**, Lansdale, PA (US)

(73) Assignee: **Lutron Technology Company LLC**, Coopersburg, PA (US)

(**) Term: **15 Years**

(21) Appl. No.: **29/827,976**

(22) Filed: **Feb. 23, 2022**

Related U.S. Application Data

- (63) Continuation of application No. 29/743,739, filed on Jul. 23, 2020, now Pat. No. Des. 947,234.

CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines illustrate a display screen or portion thereof, and form no part of the claimed design.
